UNITED STATES PATENT OFFICE.

MATTIE WILLIAMS, OF BERTHA, MISSOURI, ASSIGNOR OF ONE-HALF TO J. L. NICHOL,
OF BERTHA, MISSOURI.

TOY.

1,123,637.

Specification of Letters Patent.

Patented Jan. 5, 1915.

Application filed August 14, 1913. Serial No. 784,823.

To all whom it may concern:

Be it known that I, MATTIE WILLIAMS, a citizen of the United States, residing at Bertha, in the county of Douglas, State of Missouri, have invented certain new and useful Improvements in Toys; and I do hereby declare the following to be a full, clear, and exact description of the invention, such as will enable others skilled in the art 10 to which it appertains to make and use the same.

This invention relates to toys of the jointed figure type.

An object of the present invention is to 15 provide a dancing figure toy that may be operated from a vibratory board which is struck by the governor balls of a graphophone whereby upon the graphophone being played the jointed figure will simulate a 20 dance to the music.

A further object of the invention is to provide a toy of this character that may be attached to graphophones now in use without extensive alterations.

25 A further object is to provide a device of this character that will be formed of a few simple and inexpensive parts that will not easily get out of order.

With the above objects in view the invention 30 consists of certain novel details of construction and combination of parts herein-after fully described and claimed, it being understood that various modifications may be made in the minor details of construction 35 within the scope of the appended claims.

In the accompanying drawing illustrating 40 this invention:—Figure 1 is a side elevation showing the application of a toy to a disk graphophone. Fig. 2 is a fragmentary horizontal section taken on the line 2—2 Fig. 1 showing the vibratory board and governor of the graphophone. Fig. 3 is a longitudinal sectional view on the line 3—3 Fig. 2. Fig. 4 is a front elevation of the 45 dancing figure. Fig. 5 is a fragmentary view showing the joints of the figure's legs. Fig. 6 is a fragmentary view showing one of the arm joints.

Referring now to the drawing in which 50 like characters of reference designate similar parts, 10 designates in general an ordinary disk graphophone. In carrying out my invention I provide a spring board 11 which is provided at one end with a curved 55 attaching foot 12 that is secured by screws

13 or otherwise to the bottom of the graphophone casing in such a manner that the spring board projects forwardly over the governor balls 14 of the graphophone lightly touching the governor balls, and projects at the free end horizontally out of a slot 15 in the side of the graphophone casing. It is evident that when the graphophone is running that the governor balls during their rotation will beat a tattoo on 60 the bottom face of the spring board with a resultant vibratory motion being imparted to the latter.

A dancing figure or doll 16 is yieldably supported upon a spring arm 17 that is attached to the back of the body 18 of the doll and is attached to the top of the graphophone casing above the spring board 11. The arm joints and leg joints of the doll are articulated, being interfitted in tongue and 70 groove construction as shown at 19 and 20 with pivot pins 21 passed through the tongues and grooves. By virtue of the doll being held upright at the back with the feet loosely bearing upon the spring board, a 75 motion as of jiggling will be imparted to the doll by the vibratory movement of the spring board.

From the above description it will be seen that I have provided an exceedingly amus- 80 ing and simple toy that may be attached to graphophones of ordinary type without alteration and which toy will be inexpensive to manufacture and formed of a few parts 85 that will not easily get out of order. 90

What is claimed, is:—

1. The combination with a graphophone of a toy in the nature of an articulated doll, and a vibratory spring board lightly bearing upon the graphophone governor balls 95 and actuated by the latter to impart a jiggling movement to the doll.

2. The combination with a graphophone of a toy in the nature of an articulated doll, means for yieldably attaching the body of 100 the doll to the graphophone casing, and a vibratory spring board within said casing attached at one end to the casing and having the free end bearing lightly upon the graphophone balls and passed through a 105 slot in said casing, and lightly touching the feet of said doll, rotation of said balls imparting a vibratory movement to said board with resultant imparting of a jiggling movement to said doll. 110

3. In combination with a graphophone, an articulated figure resiliently suspended from a portion of the graphophone casing and means operable by the mechanism of the graphophone for imparting motion to said figure, said means comprising a resilient member secured within the graphophone casing and extending outwardly through a slot therein and contacting with the 10 said figure, said strip being engaged by the

governor balls of the graphophone mechanism during their rotation whereby the vibration of said strip will agitate said figure.

In testimony whereof, I affix my signature, in the presence of two witnesses.

MATTIE WILLIAMS.
